TOY AUTOMATIC RIFLE

Joseph P. Walczak, Baltimore, Md.

Application January 25, 1939, Serial No. 252,822

6 Claims. (Cl. 124—27)

My invention relates broadly to toy fire arms, and more particularly to a toy gun in the nature of a child's gun of the magazine type.

An important object of my invention is the provision of a toy gun that is at once harmless and a source of great entertainment and amusement.

Another object of my invention is the provision of a toy gun wherein the loading and cocking action may be accomplished simultaneously.

Yet another object of my invention is the provision of a toy gun that is durable, efficient, and easy to operate.

Other objects and advantages of my invention will be apparent during the course of the following description.

In the drawings, forming a part of this specification, and in which like numerals are employed to designate like parts throughout the same,

Figure 1 is a side elevation of my device, and showing parts broken away,

Figure 2 is a top plan view thereof,

Figure 3 is a fragmentary longitudinal sectional view of my device,

Figure 4 is a view similar to Figure 3, but on a larger scale thereof,

Figure 5 is a transverse sectional view, taken on the line 5—5 of Figure 4,

Figure 6 is a transverse sectional view, taken on line 6—6 of Figure 3,

Figure 7 is a transverse sectional view, taken on line 7—7 of Figure 3,

Figure 8 is a fragmentary longitudinal sectional view, taken on line 8—8 of Figure 1,

Figure 9 is a perspective view of the projector, embodying a part of my invention, and

Figure 10 is a perspective view of the rotary feeder, embodying a part of my invention.

In the accompanying drawings, wherein for the purpose of illustration, is shown a preferred embodiment of my invention, the numeral 10 represents the stock of the gun, which is formed in two superimposed sections 11 and 12 of conventional design each of the sections being fashioned with a handle portion 13, and a forearm portion 14 extending forwardly of the handle portions and with the top edges thereof arcuately recessed, as at 15. The forward end of the forearm portions 14 are formed with a forwardly projecting shank 16 adapted to be received within the segmental pocket 17 of the barrel 18. The barrel 18 is tubular in its formation, and lies within the arcuate recess 15 with the forward end 19 projecting a substantial distance beyond

the end of the stock 10. The barrel is equipped with a forward sight member 20 projecting vertically therefrom. Bolt and nut 21 and 22 extends transversely through the handle portion of the stock to securely hold the sections 11 and 12 together and to maintain the various appurtenances positioned therebetween in their properly related places, and the forearm portion of the section 11 is provided adjacent its forward end with a transversely projecting pin 23 which is received in a registering opening in the section 12 to hold the forward ends of the forearm portion of the sections in correct alignment.

A magazine 24 is fastened to the stock rearwardly of the rearward end 25 of the barrel and includes an inverted U-shaped bottom support 26 adapted to embrace the sides of the stock and to be fastened thereto by means of the screws 27, or the like. A tubular portion 28 is connected to the U-shaped support 26 by means of vertical end flanges 36 and 37, and has a longitudinally extending lower slot 29, and a loading opening 30 in its top edgacent the back thereof. A pair of spaced lugs 31 and 32 depend from the interior of the tubular portion rearwardly of the loading opening 30. A longitudinally extending pin 33 is supported by the lugs and the forward end thereof normally projects across the loading opening 30. A shoulder 34 is formed on the pin and is normally held in abutting relation with the inner face of the lug 32 by means of a coil spring 35 interposed between the shoulder and lug 31. The flanges 36 and 37 space the tubular portion 28 a substantial distance above the support 26 and interposed therebetween is a longitudinally extending rod 38 having its opposite ends supported by the said flanges. The follower 39 is formed with a tubular section 40 slidable on the rod 38 and formed with an arcuately formed neck 41 which extends upwardly therefrom through the longitudinal slot 29 and into the tubular portion 28 where it terminates in a circular head 42. Extending laterally of the tubular portion 40 of the follower 39 is a finger piece 43 which comprises a means whereby the follower may be retracted against the resilient action of a coil spring 44, interposed between the vertical flange 36 and the follower. The spring catch 45 has the end 46 thereof securely fastened to the underside of the U-shaped support 26; and the intermediate portion thereof is bent upwardly through an opening in the support to define the catch 47, the rearwardly extending end 48 of which projects upwardly through a second opening in the support 26 and laterally from the side 55

thereof. When the follower 39 is retracted against the resilient action of coil spring 44, the laterally extending finger piece 43 is adapted to engage behind the spring catch 47. The follower 39 is released by manually depressing the laterally extending end 48 of the spring latch 45. During the process of retracting the follower, the neck 41 will engage the depending shank 49 carried by the pin 33 to retract the said pin against action of the coil spring 35. In the fully retracted position, the head 42 of the follower will be positioned rearwardly of the opening 30 and pin 33 will be automatically moved away from its blocking position across the said opening. Projectiles 50 may now be introduced through the loading opening 30 and into the tubular portion 28.

The rotary feeder 51 is positioned adjacent the forward end of the tubular portion 28, and comprises a central hub 52 formed with longitudinally extending end shanks 53 and right angularly disposed blades 54, 55, 56 and 57. The blades 56 and 57 are joined at their outer ends by an arcuately formed, integrally connected segmental wall 58. The end shanks 53 of the feeder are positioned in horizontally aligning openings in the sides of the tubular member 28, and a spring 59 has the end 60 thereof attached to the tubular member and with the intermediate portion wound about the hub 52 between the blades and side wall of the tubular member, and with the end 61 thereof bent inwardly behind the plate 56. The spring 59 holds the rotary feeder normally motionless and with the foremost of the projectiles 50 positioned between the arm 54 and 57.

The stock 10 is formed with a longitudinally extending bore 62 which terminates adjacent the opposite ends of the forearm portion 14. The rod 63 is axially positioned therein and carries plates 64' and 65' thereon in abutting relation with the end walls of the bore. A projector 64 is slidably mounted on the rod and includes a tubular portion 65 having an abutment 66 formed on its bottom side and a longitudinally extending shank 67 extending rearwardly therefrom and with the extremity 68 thereof formed of greater thickness than the shank 67 and with the abutment 69 of the said end extending vertically from the underside of the shank 67. A fin 70 projects from the upper side of the tube 65 and is formed with a rearwardly sloping rear portion 71. The top 72 slopes downwardly to the vertical front wall 73, and is formed adjacent the rear wall 71 with a slanted recess 74 to define the extension 75. The semi-tubular ball carrier 76 is integrally formed on the forward end of the fin 70, and has the forward end 77 thereof projecting a substantial distance beyond the said fin. A coil spring 78 is interposed between the plate 64' and the rear of the tubular portion 65 of the projector 64, and a recoil spring 79 is carried by the rod 63 forwardly thereof in abutting relation to the plate 65'.

The bottom of the forearm 14 is provided with a longitudinally extending slot 80 of substantially the same length as the bore 62. The hand piece 81 is provided with a pair of spaced vertically extending pins 82 and 83 slidably positioned in the slot 80, and plate 84 is positioned intermediate the pins 82 and 83. The plate 84 is formed with a horizontally disposed top plate 85 adapted to extend on either side of slot 80 and to hold the piece 81 securely positioned within the slot. The pin 23 in the forward end of the forearm portion

14 of the stock is provided with a spring clip 86 adapted to engage the pin 83 when the hand piece 81 is in the forward end of the slot and to hold the same against unconstrained reciprocating movement therein. Plate 85 extends rearwardly of plate 84 and the projecting end thereof is enlarged toward its extremity to form an abutment 86'.

The slot 80 is widened adjacent the rearward end to receive the trigger piece 87 which is formed with a channel 88 provided with a transversely extending pin 89, the opposite ends of which extend into aligning apertures in the sides of the slot 80. The trigger 90 is pivoted on pin 89 and is formed with a forwardly extending projector 15 release 91, the end of which bears against the leaf spring 92 comprising a rearwardly bent continuation of the forward end of the trigger piece. A stop 93 projects upwardly from the end of the spring 92. The trigger 90 is formed rearwardly of the release 91 with shank 94 which abuts the inner face of the channel 88 to limit the forward movement of finger piece 95 which projects through slots 96 in the channel. A trigger guard 97 is secured to the underside of the stock, and prevents promiscuous actuation of the trigger.

When the hand piece 81 is manually retracted in the slot 80 the abutment 86' will engage the abutment 66 on the projector and cause the same to be retracted therewith against the resilient action of the spring 78. When the projector 64 has been retracted a sufficient distance, the abutment 69 of the shank 67 will engage the stop 93 on spring 92 to hold the projector retracted independently of the hand piece 81. The resiliency 35 of the spring 92 will hold the stop 93 in firm interlocking engagement with the abutment 69 until released therefrom by the trigger 90. The forward end of the trigger bears against the end of the spring 92 and a rearward pull on the finger piece 40 95 will depress the spring sufficient to release the abutment 69. In the process of retracting the projector, the extension 75 of the fin 70 will engage the blade 56 of the rotary feeder 51. Upon contact with the extension, the feeder will be rotated and upon further retraction of the projector the portion 96 of the fin 70 will contact the blade 55 to further rotate the feeder until the end of the blade 54 contacts the rearward edge of the ball carrier 76. When the rotor is normally positioned the foremost projectile is positioned between blades 54 and 57 so that when the projector has been completely retracted the ball positioned between plates 54 and 57 will be deposited in the ball carrier 76. The arcuate wall 58 joining the plates 56 and 57 will prevent any other of the projectiles within the cylinder 28 from being received within the rotary feeder until the same has been released by the forward movement of the projector.

The leaf spring 97 has the end 98 thereof bent downwardly in a U-shaped formation to cover the rearward end of the barrel 18 so that when the projector is completely retracted and with the abutment 69 in interlocking engagement with the stop 93, the ball carrier will be positioned rearwardly of the spring clip 97 in a manner whereby the downwardly extending end 98 will hold the projectile deposited within the ball carrier by projector 64, and prevent the said projectile 70 from rolling out the open end of the barrel. The magazine is provided with a cover 99 having a rear sight 100 formed thereon. The cover 99 is formed with a transverse rear wall 101 which effectively closes the rear of the magazine, and the side walls 75

are provided with tabs 102 which are attached to the stock 10 by means of the screws 103, or the like.

It may be readily seen that a plurality of projectiles may be deposited in the magazine, and that when the hand piece 81 is manually retracted, the abutment 69 of the projector will engage the stop on the trigger spring 92 to hold the projector in a fully retracted position against the resilient action of the coil spring 78. While this action is occurring the fin 70 of the projector will rotate the rotary feeder 51 to deposit the foremost of the projectiles in the magazine within in the ball carrier 76. The projectile will be held therein by spring 99 pending release of the projector. Upon movement of the trigger 91 the stop 93 will release the projector and the compressed spring 78 will force the same forwardly with sufficient velocity to discharge the projectile from the end of the barrel. The recoil spring 79 is preferably heavier than spring 78, and the resilient action thereof will effectively stop the projector 64. When the projector is released, the spring 59 will rotate the feeder to the normal position so that another of the projectiles will automatically be positioned between blades 54 and 57.

It is to be understood that the form of my invention herewith shown and described is to be taken as a preferred example of the same, and that various changes in the size, shape and arrangement of parts may be resorted to without departing from the spirit of my invention or the scope of the appended claims.

Having thus described my invention, I claim:

1. In a toy rifle having a barrel and a magazine provided with an outlet vent through which projectiles may pass into the barrel, means for singly feeding the projectiles from the magazine to the barrel comprising a feeder oscillatively mounted below the outlet vent, said feeder being formed with radial blades defining quadrantal pockets one of the pockets thus formed being closed by a web connecting the free ends of the adjacent blades, said feeder being normally positioned with the closed pocket disposed below the outlet vent and with the adjacent pocket in register with the vent to receive the foremost projectile in the magazine whereby a partial rotation of the feeder in a clockwise direction will deposit the said foremost projectile in the barrel and move the web of the closed pocket into obturating relation to the outlet vent of the magazine.

2. In a toy rifle having a barrel and a magazine provided with an outlet vent through which projectiles may pass into the barrel, means for singly feeding the projectiles from the magazine to the barrel comprising a feeder oscillatively mounted below the outlet vent, said feeder being formed with radial blades defining quadrantal pockets one of the pockets thus formed being closed by a web connecting the free ends of the adjacent blades, spring means coactive with the feeder to permit free oscillation of the same but normally positioning the same with the closed pocket below the outlet vent and the adjacent pocket in register with the vent to receive the foremost projectile, whereby rotation of the feeder in a clockwise direction will deposit the foremost projectile into the barrel and simultaneously move the web of the closed pocket into obturating relation to the outlet vent, the resilient action of the spring thereafter reversely rotating the feeder to the initial position.

3. In a toy rifle having a barrel and a maga-

zine provided with an outlet vent through which projectiles may pass into the barrel, means for singly feeding the projectiles from the magazine to the barrel comprising a feeder oscillatively mounted below the outlet vent, said feeder being formed with radial blades defining quadrantal pockets one of the pockets thus formed being closed by a web connecting the free ends of the adjacent blades, spring means coactive with the feeder to permit free oscillation of the same but normally positioning the same with the closed pocket below the outlet vent and the adjacent pocket in register with the vent to receive the foremost projectile, a carriage mounted for sliding movement below the barrel, parts of said carriage being engageable with the feeder during the travel of the carriage to partially rotate the feeder against the resilient action of the spring means to deposit the foremost projectile in the barrel and to simultaneously move the web of the closed pocket into obturating relation to the outlet vent, the resilient action of the spring thereafter reversely rotating the feeder to the initial position.

4. In a toy rifle having a barrel and a magazine provided with an outlet vent through which projectiles may pass into the barrel, means for singly feeding the projectiles from the magazine to the barrel comprising a feeder oscillatively mounted below the outlet vent, said feeder being formed with radial blades defining quadrantal pockets one of the pockets thus formed being closed by a web connecting the free ends of the adjacent blades, spring means coactive with the feeder to permit free oscillation of the same but normally positioning the same with the closed pocket below the outlet vent and the adjacent pocket in register with the vent to receive the foremost projectile, a spring influenced carriage mounted for sliding movement below the barrel, parts of said carriage being engageable with the feeder during the travel of the carriage to partially rotate the feeder against the resilient action of the spring means in a manner to deposit the foremost projectile in the barrel and to simultaneously move the web of the closed pocket into obturating relation to the outlet vent, a manually releasable catch automatically engageable with the carriage at the termination of its travel whereby release of the carriage from the catch will permit the said carriage to move in a direction to release the feeder and the resilient action of the spring means thereafter reversely rotating the feeder to the initial position.

5. In a toy rifle having a barrel and a magazine provided with an outlet vent through which projectiles may pass into the barrel, means for singly feeding the projectiles from the magazine to the barrel comprising a feeder oscillatively mounted below the outlet vent, said feeder being formed with right-angularly disposed diametrically opposed radial blades defining quadrantal pockets one of the pockets thus formed being closed by a web connecting the free ends of the adjacent blades, said feeder being normally positioned with the closed pocket disposed below the outlet vent and with the adjacent pocket in register with the vent to receive the foremost projectiles in the magazine, a carriage mounted for sliding movement below the barrel, said carriage being formed with substantially parallel extensions spaced apart to define an interstice therebetween, one of the extensions being engageable with a blade of the feeder during the travel of the carriage to rotate the adjacent blade of

the feeder into the interstice between the extensions, the second extension thereafter engaging the last-mentioned blade to further rotate the feeder to deposit the foremost projectile into the barrel and to simultaneously move the web of the closed pocket into obturating relation to the outlet vent.

6. In a toy rifle having a barrel and a magazine provided with an outlet vent through which projectiles may pass into the barrel, means for singly feeding the projectiles from the magazine to the barrel comprising a feeder oscillatively mounted below the outlet vent, said feeder being formed with right-angularly disposed diametrically opposed radial blades defining quadrantal pockets one of the pockets thus formed being closed by a web connecting the free ends of the adjacent blades, spring means coactive with the feeder to permit free oscillation of the same but normally positioning the same with the closed

pocket below the outlet vent and the adjacent pocket in register with the vent to receive the foremost projectile, a carriage mounted for sliding movement below the barrel, said carriage being formed with substantially parallel extensions spaced apart to define an interstice therebetween, one of the extensions being engageable with a blade of the feeder during the travel of the carriage to rotate the adjacent blade of the feeder into the interstice between the extensions, the second extension thereafter engaging the last-mentioned blade to further rotate the feeder to deposit the foremost projectile into the barrel and to simultaneously move the web of the closed pocket into obturating relation to the outlet vent, the resilient action of the spring means thereafter reversely rotating the feeder to the initial position.

JOSEPH P. WALCZAK. 20
